UNITED STATES PATENT OFFICE.

JAMES A. MACKENZIE, OF MINNEAPOLIS, MINNESOTA.

HINGE-MORTISING MACHINE.

SPECIFICATION forming part of Letters Patent No. 355,272, dated December 28, 1886.

Application filed August 3, 1886. Serial No. 209,910. (No model.)

To all whom it may concern:

Be it known that I, JAMES A. MACKENZIE, of Minneapolis, in the county of Hennepin, State of Minnesota, have invented a new and useful Hinge-Mortising Machine, of which the following is a specification.

This invention relates to improvements in machines for cutting hinge gains or mortises; and the object I have in view is to provide a machine with which a mortise of any depth and width may be made at a single operation.

The invention consists, generally, in a mortising machine having fixed knives or cutters for making the incisions that form the boundaries of the gains, and a knife sliding substantially at right angles thereto for removing the wood that is within such incisions.

The invention further consists in the novel construction and arrangement of the gages for regulating the width and depth of the mortise.

The invention further consists in a novel knife-clamp for holding the fixed knives in position.

The invention further consists in the construction and combination hereinafter described, and pointed out in the claims.

In the accompanying drawings, forming part of this specification, Figure 1 is a side elevation of my improved device. Fig. 2 is a front elevation, and Fig. 3 is a rear elevation, of the same. Fig. 4 is a bottom plan, and Fig. 5 is a partial vertical section, showing the sliding knife and the knife-stock and clamp for holding the fixed knives in position.

In the drawings, 2 represents the main frame of the device. It is preferably formed of cast metal and is provided with a suitable handle, 3, by which it may be grasped by the hand of the operator and placed and held in any desired position.

The bottom of the frame 2 is formed as a three-sided box, having two sides, 5 5, parallel to each other, and the side 7 at right angles to the sides 5 5, thereby forming a knife-stock, against the inner walls of which the knives are clamped by a block of metal that fits closely inside of the knives and presses them firmly against the outer box-shaped stock, which takes the place of the knife-caps used on most machine-knives or plane-bits. This box or stock is preferably formed integrally with the frame 2, and its walls inclose a rect-

angular space between them. The inner walls of the stock are vertical, and the fixed knives 9 are arranged within them, with their flat 55 sides against the vertical walls. The other sides of the knives are inclined, which causes the knives to be thicker at the back, or, in other words, to have a wedge shape, as shown in Figs. 2 and 5. A clamping-block, 11, having the wedge-shaped sides 13, is placed within the knives 9, and is fastened to the frame 2 by a screw, 15. By this means the knives 9 are rigidly secured between the walls 5 and 7 and the clamping-block 11. I avoid slotting the 65 knives and using separate screws for holding them in place, and also avoid using caps.

Should the knives become loose, small pieces of leather or other material may be placed between them and the inclined walls of the 70 clamping-block, and similar pieces may be placed behind the knives when they become worn, so as to be too short for use.

The fixed knives are arranged on the three sides of a rectangle, and by them the vertical, 75 incisions for the mortises are made.

17 is a sliding knife that is supported and moves freely in ways 19, formed on the frame 2. This knife is arranged substantially in line with the lower edges of the fixed knives and 80 is adapted to move into the rectangular space between them.

Suitable means are provided for moving the knife 17. I prefer to provide the knife with the lugs 21 and to fulcrum a lever, 23, upon 85 the frame 2, with its end between the lugs 21. By moving the upper end of the lever outward from the frame-handle 3 the knife 17 is moved inward between the other knives, cutting clean the chip to be removed; and by reversing the 90 movement of the lever the knife is moved in the other direction, ready for the next operation.

The sliding knife may be arranged to move exactly at right angles to the other knives, or 95 it may be slightly inclined, as shown in Fig. 5, so that it will cut deeper at the front or forward edge than at the rear. This makes the mortise somewhat deeper in front, which is usually desirable.

In using the device the bottom of the frame is placed on the edge of the door, casing, lid, or wherever the mortise is to be made. By striking with a mallet on the end of the handle

3 the knives 9 are driven into the wood to the desired depth. While the tool is held in this position the lever is operated, sliding the knife 17 between the other knives, and thereby cutting out the wood to the proper depth. The knife 17 is then moved back and the device is ready for another operation. It is found that the wood removed by the tool usually sticks between the fixed knives, and I prefer to provide a chip-expeller by which it may be pushed out. This preferably consists of a plunger, 27, secured to a pin, 29, that projects through the frame into the space between the fixed knives. A spring, 31, upon the pin holds it in an elevated position. By pressing on the end of the pin the block 27 may be forced against a chip between the fixed knives to push it therefrom. I also prefer to provide the device with gages for limiting the width and depth of the mortise.

33 is a depth-gage held to the frame 2 by the screw 35 and provided with a slot, 37, which allows a certain lateral movement. The frame 2 is recessed to receive the gage, and this recess is formed with inclines 39 upon either side, the angles of which are exactly the same. These inclines are arranged to fit corresponding inclines, 34, upon the upper extremities of the gage 33. The gage is provided with a projection, 41, having a threaded opening, into which a set-screw, 43, is fitted. The inner end of this set-screw bears against the frame 2. The lower portion of the gage 33 is preferably provided with two bearing ends, 45, the under surfaces of which rest upon the work, the distance between the lower surface of the sliding knife and the surface of the ends 45 determining the depth of the mortise. To vary this depth the screw 35 is loosened, and by turning 40 the set-screw 43 the gage may be moved to the right or left upon the inclines 39. This carries the surface of the gage up or down, as the case may be, and increases or diminishes the depth of the incision.

45 I also provide the device with a gage, 47, to determine the width of the cut to suit the particular hinge to be used. This gage consists of a plate extending across the bottom of the frame and having ways upon either side which 50 bear upon the frame and keep it parallel thereto. It is held to the frame by means of the screw 49, which operates in the slot 51, and allows the gage to be moved backward or forward, as desired. Projections 53 are placed 55 upon the front of this gage at right angles to the cut. These projections bear against the work, and the distance from the outer knife to the projection will be the width of the recess required to receive the hinge.

60 The device may be used for cutting gains or mortises of any desired length, as two or more cuts may be made contiguous to each other when one cut is not of sufficient length.

I claim as my invention—

65 1. In a device for forming hinge-mortises, the combination, with the frame 2, having the

handle 3, and the rectangular stock formed integrally with said frame, of the fixed knives arranged against the three sides of said stock, and the sliding knife mounted in ways on the frame 2 and adapted to move between the fixed knives, substantially as described.

2. The combination, in a hinge-mortiser, with the frame 2, having the handle 3, and the rectangular stock formed integrally with said frame, of the fixed knives 9, secured to said stock, the sliding knife 17, mounted in ways 19 in the frame 2 and arranged in a plane at or near the edges of the fixed knives, and means for moving said sliding knife.

3. The combination, with the frame 2, having the handle 3, and the rectangular stock formed integrally with said frame, of the wedge-shaped knives 9, arranged within said walls, the clamping-block 11, having the inclined walls 13, and the screw 15, all substantially as described.

4. The combination, in a hinge-mortiser, with the frame 2, having the handle 3, and the rectangular stock formed integrally with said frame, of the fixed knives 9, secured to said stock, the sliding knife 17, mounted in ways 19, formed in said frame 2, and the operating-lever 23, pivoted to the frame 2 and engaging said sliding knife, all substantially as described.

5. The combination, in a hinge-mortiser, with the frame 2, having the handle 3, of the knives 9, secured, as described, to said frame, the sliding knife 17, mounted in ways 19 in said frame, the depth-gage 33 and the width-gage 47, secured to said frame 2, and means for moving said gages, all substantially as described.

6. The combination, with the fixed knives 9 and the sliding knife 17, of the frame having the inclines 39, the depth-gage having the bearing ends 45 and the inclines 34, and the adjusting-screw 43, for moving said gage, substantially as described.

7. The combination, with the fixed knives 9 and the sliding knife 17, of the width-gage 47, adapted to move in a plane at right angles to the fixed knives and having the bearing ends 53 upon each side of the knives, substantially as described.

8. The combination, in a hinge-mortiser, with the frame 2, having the handle 3, and the rectangular stock formed integrally with said frame, of the fixed knives secured to said stock, the spring-controlled plunger 27, arranged within said fixed knives, and the sliding knife 17, moving at right angles to the fixed knives in ways formed in the frame 2, all substantially as described.

In testimony whereof I have hereunto set my hand this 22d day of July, 1886.

JAMES A. MACKENZIE.
